UNITED STATES PATENT OFFICE.

EGBERT H. AVERY, OF BELVIDERE, ILLINOIS.

IMPROVEMENT IN APPARATUS FOR MOVING BUILDINGS.

Specification forming part of Letters Patent No. **58,970**, dated October 23, 1866.

To all whom it may concern:

Be it known that I, EGBERT H. AVERY, of Belvidere, in the county of Boone and State of Illinois, have invented a new and useful Improvement in Apparatus for Moving Buildings; and I do hereby declare that the following is a full, clear, and exact description of the construction and operation of the same, reference being had to the annexed drawings, and letters of reference marked thereon, making a part of this specification, in which—

Figure 1 is a plan view of my apparatus for moving buildings. Fig. 2 is a perspective representation of one of the trucks. Fig. 3 is an elevation of the front or guide trucks.

The nature of my invention consists in guide-keys so arranged as to hold the trucks at any desired angle relative to the sills of the building, in order that it may be made to move in a straight line or be turned around.

By means of these devices and arrangements a much better apparatus is provided for moving wooden buildings than any now in use, for when the trucks are set under the sill at the points where the building most requires support they will remain in such position and operate without any attention so long as the building is moving in a straight line, and can also be adjusted by means of the guide-keys, for carrying the rear end of the building laterally in one direction while the front end is moving in the opposite direction, thus providing means for turning or moving a building in any direction required.

To enable others skilled in the art to make and use my invention, I will describe the method of construction and operation.

A, Fig. 1, represents the sills of the building to be moved, and Fig. 3 an elevation of

the guide-trucks, connected together by means of the broad platform I and the pivot F'. This platform is elevated at a, in order that the guide-trucks may pass over uneven ground, and yet be turned in any direction necessary for guiding the building.

It will be seen that the pivot F stands in front of the axle of the rear guide-truck, by which means the roller is prevented from turning sidewise when in motion. The forward guide-truck is kept in the proper direction by means of the side guide, G, which is attached to the frame C.

Fig. 2 shows the roller adjusted in the frame C, the front side of which supports the pivot E, which enters the sills A, as seen at Fig. 1.

C' C', Fig. 1, represent the double truck pivoted to the sill A at K. The direction which this truck is to move can be given by adjusting the keys D between the sill A and pins d, as seen at Fig. 1.

L is the tie-rope, to which the draft-rope P is attached, the object being to apply the power so far back as to prevent the forward trucks from being upset when turning the building around.

No definite instructions can be given for moving buildings with my apparatus. Any number of trucks can be used and guided, as set forth, without any special instruction.

Having thus fully described my invention, what I claim, and desire to secure by Letters Patent of the United States, is—

The guide-keys D, in combination with the trucks C' C', B, substantially as set forth.

EGBERT H. AVERY.
